ILLUMINABLE DISPLAY DEVICE

Leon H. Foster, Brooklyn, N. Y.

Application December 17, 1947, Serial No. 143,188

Term of patent 3½ years

(Cl. D14—18)

To all whom it may concern:

Be it known that I, Leon H. Foster, a citizen of the United States of America, residing at Brooklyn, N. Y., in the county of Kings, and State of New York, have invented a new, original, and ornamental Design for Illuminable Display Device, of which the following is a specification, reference being had to the accompanying drawing, forming part thereof.

Fig. 1 is a side perspective view of an illuminable display device showing my new design;

Fig. 2 is a top perspective view; and

Fig. 3 is a sectional view taken in line 3—3 of Fig. 1.

The drawing has been shaded to show contrasting appearance.

I claim:

The ornamental design for an illuminable display device, substantially as shown and described.

LEON H. FOSTER.
